UNITED STATES PATENT OFFICE.

WILLIAM B. BOLLES, OF MILWAUKEE, WISCONSIN.

ANTIPANIC-LOCK-OPERATING MECHANISM.

Application filed December 15, 1923. Serial No. 680,889.

This invention relates to anti-panic lock operating mechanisms and more particularly to the lock operating devices adapted to be applied to the ordinary type of door locks and latches and to provide ready exit at all times.

The present invention is an improvement over the invention disclosed in my co-pending application, Serial No. 572,178, filed

10 July 1, 1922, and is in part a continuation of said application.

In my co-pending application above referred to I have disclosed a lever actuated lock operator in which the action of the actuating lever is cushioned to protect both the lock actuating mechanism and the mechanism of the lock against excessive shock due to violent actuations of the lever or application of excessive force thereto. 15 In the various modifications of the invention disclosed in said application the casing of the lock actuating mechanism was shown secured to the door in a position overlying the lock casing and attached to the door 20 above and below the casing. This mounting of the lock actuating mechanism prevented the use of this device with locks of the type having cylinders projecting to opposite sides of the faces of the door for locking and unlocking from the inside as well as the outside. 25 The present invention has for an object to provide a lock actuating mechanism adapted to be secured to the door at one side of the lock casing and clear of any inner lock cylinder of the lock, permitting the use 30 of the lock actuating device with doors having locks operable from either the outside or inside.

A further object of the invention is to 40 provide a lock actuating mechanism of the double acting type in which the actuating lever may be moved in either direction from a neutral position to release the lock and to provide a cushioning device adapted to 45 cushion the action of the lever in either direction.

A more specific object of the invention is to provide a double acting lock actuator in 50 which a single spring is interposed between the actuating lever and lock actuating member in such a manner that the movement of the lever in either direction is cushioned and the mechanism thereby protected against damage due to violent operations of the 55 lever.

With these and other objects in view this invention may be said to comprise the device as illustrated in the accompanying drawings hereinafter described and specifically set forth in the appended claims together with such variations and modifications thereof as will be apparent to one skilled in the art to which the invention 60 pertains.

Reference should be had to the accompanying drawings in which Fig. 1 is an elevation of a door with the lock actuating mechanism attached thereto. Fig. 2 is a fragmentary edge elevation showing the door, door latch and lock actuating mechanism, a portion of the door and lock actuator being broken away to show the lock actuating mechanism in section. Fig. 3 is a fragmentary front elevation of a portion of the door showing the lock and a portion 70 of the lock actuator, a portion of the actuator being broken away and shown in section. Fig. 4 is a rear elevation of the actuator detached from the door. Figs. 5 and 6 are detail views showing an auxiliary lever 75 counterbalancing spring. Fig. 7 is an edge view similar to Fig. 2 showing a lock actuating mechanism of the double acting type. Fig. 8 is a rear elevation of the actuator detached from the door. Fig. 9 is a 80 detail view of the actuator slide with a portion broken away and shown in section.

Referring to the accompanying drawings, Fig. 1 shows a door 1, which is hinged and mounted between the usual door jambs 2. 90 In the edge of the door there is mortised a lock casing 3, this lock being of a well known type which may be purchased on the open market. The door lock consists of a latch 4 which projects from the edge of the 95 lock casing and is adapted to be locked by suitable mechanism within the lock casing in projecting position to lock the door against opening. The door lock is provided with a trip member 6, which when moved in 100 an upward direction is adapted to release the latch locking mechanism and operate the latch to permit the door to open.

The lock actuating mechanism forming the subject matter of the present invention 105 is mounted within a suitable casing 7, which is provided adjacent to the lower corners thereof and at the sides thereof at points spaced downwardly from the upper end of the casing with screw receiving bosses 8, 110

through which suitable screws may be passed to secure the casing to the inner face of the door 1. Within the casing 7 there is a vertically disposed longitudinally movable slide 9 which carries a projection 10 adjacent to its upper end, which extends through a slot in the inner wall of the casing 7 into a recess 11 formed in the door adjacent to the lower edge of the lock casing. 5 This projection 10 co-acts with the trip member 6 of the lock to release the latch 4. The slide 9 actuates the door lock when it is moved in an upward direction and is normally held in a position in which the projection 10 is in the lower portion of the recess 11, free of the trip member 6, by means of a compression spring 12 which is mounted within a recess 13 in the upper end of the slide 9. The spring 12 as shown in Figs. 2, 10 3 and 4 may be entirely within the recess 13 and may engage at its upper end with a plunger 14 which is loosely and slidably mounted on the upper end of the recess 13 and bears against the upper end wall of the 15 actuator casing 7. Beneath the spring recess 13 the slide 9 is provided with an elongated, rectangular slot 15 in which is slidably mounted a block 16, which is inserted beneath a coil spring 17, which fits 20 between the side walls of the slot and bears at its upper end against the upper end of the slot and at its lower end upon the upper face of the block 16. The lower face of the block 16 is pressed by the spring 17 25 against a projection 19 of a lever 20, which is pivoted at 21 to a boss 22 formed upon the outer face of the casing 7. The projecting portion 19 of the lever 20 is normally held against the lower end of the slot 15 in the slide 9 by the spring pressed block 16. The lever 20 is normally held by the slide 9 in a position in which its outer end is somewhat below the pivot 21 and its upward movement is limited by the upper portion 30 of the boss 22. From this position the lever 20 may be swung downwardly toward the face of the door to move the slide 9 upwardly to release the lock. At its outer end the lever 20 may be provided with a boss 45 23 adapted to receive a push bar 24 which extends horizontally along the inner side of the door and is connected at its opposite end to an arm 25 which corresponds to the outer portion of the lever 20 and which is pivoted to a bracket 26 fixed to the inner face of the door adjacent to the hinged edge thereof. 50 When the lever 20 is swung downwardly and inwardly toward the door by pushing the push bar 24 inwardly toward the door, the projecting portion 19 of the lever which lies within the slot of the slide 9 is moved upwardly and pushes against the end face of the slide block 16. This pressure is 55 transmitted through the coil spring 17 to slide 9 causing the slide to move upwardly, moving the projection 10 into engagement with the trip 6 and lifting the trip to release and retract the latch. The spring 17 is stronger than the return spring 12 so 70 that in normal operation the slide 9 will move upwardly with the projecting portion 19 of the lever. In the case of violent actuation of the lever 20 or in case the lock mechanism should stick or if for any reason 75 the upward movement of slide 9 should be impeded the lock mechanism and the lock actuating mechanism will both be protected by reason of the yielding of the spring 17, which will permit the slide 16 to move upwardly in the slot 15 until the lever 20 reaches its limit of movement, thus cushioning the action of the lever 20 and preventing excessive and sudden pressures being transmitted from the slide to the lock mechanism 80 and protecting the actuating parts of the lock operating mechanism against injury. 85

In Figures 5 and 6 of the drawing I have shown an auxiliary spring for counterbalancing the actuating lever which may assist or replace the return spring 12 shown in Figures 2, 3 and 4 of the drawing. In this modification the push bar carrying arm 25 connecting the push bar to the door adjacent to the hinge is replaced by a lever 25^a, 90 on which is a projection 19^a, similar to projection 19 of the lever 20 which extends into a casing 26^a, which replaces the bracket 26 shown in Figure 1. Within the casing 26^a, there is mounted a vertical movable slide 27 which has a slot formed to receive the projecting portion 19^a of the lever. The slide 27 is pressed in a downward direction by a compression spring 28 which fits in the upper end of the casing 26^a, between the upper end of the slide 27 and the upper end of the casing. Spring 28 serves to at least partially counterbalance the weight of levers 25^a and 20 and push bar 24 and assists holding them in their uppermost position. The auxiliary spring assists in retaining the lever in its uppermost position and permits the use of a smaller return spring for the actuator slide. If desired the spring 28 may be made strong enough to entirely replace 105 the actuator return spring in the main casing. However, it is preferred to employ both springs so that the swinging push bar is 110 counterbalanced at both ends. 115

In Figures 7, 8 and 9 of the drawing I have shown a modification of the invention in which the lock actuating mechanism is double acting, the actuating lever being movable from a neutral position in either 120 direction to release the door lock. In this modification the lock actuating mechanism is mounted within a casing 30 which is screwed to the door below the lock casing in the same manner as in the modification above described. Mounted within the casing 30 125

130

there is a vertically movable slide 31 which has a lateral projection 32 adjacent to its upper end which projects through a slot in the inner wall of the casing into the recess 11 of the door and is adapted to co-operate with the trip member 6 of the lock in exactly the same manner as the projection 10 in the modification first described. The slide 31 is pressed downwardly in the casing 10 by means of a compression coil spring 33 which is seated in a recess 34 formed in the upper end of the slide 31 and bears at its upper end against the upper end of the casing 30. The slide 31 is provided with an 15 elongated notch 35 which accommodates movable parts of the lock actuating mechanism. The actuating lever 36 has a projection 37 which extends into the notch 35 and engages with operating members for the 20 slide which will now be described. Adjacent to the upper end of the notch 35 there is a transverse lever 38 which is pivoted centrally at 39 to the front wall of the casing 30. The lever 38 extends transversely across the slide 25 31 and has pivoted to its ends depending links 40 and 41 which lie along opposite sides of the slide 31. The link 40 may be provided with a bearing or guide roller 42 at its lower end engaging a side wall of the casing and has adjacent to its lower end a foot portion 43 which projects inwardly into the notch 35 of the slide. The link 41 has a projection 44 projecting inwardly therefrom and lying within the notch 35 of the slide 30 above the foot piece 43 of the link 40, the projection 44 being above the projecting portion 37 of the lever and the foot piece 43 being below the said portion of the lever. The slide 31 has a lateral projection 45 which extends into a slot 46 in the link 41 below the projection 44. The lower end portion of the link 41 is recessed and a compression coil spring 47 is interposed between the projection 45 of the slide and the lower end of the 40 link. The spring 47 reacting between the projection 45 and the lower end of the link 41 tends to force the link 41 downwardly and the downward movement of the link 41 tends to swing lever 38 about its pivot 39 and moves the link 40 upwardly. The spring 47 thus serves to normally press the projections 43 and 44 of the links against opposite sides of the projection 37 of the operating lever 36. The slide 31 is normally held by the spring 33 in a position in which the lever 36 is intermediate its upper and lower limits of movement, so that the lever 36 may be actuated in either direction from its normal or neutral position. If the lever 36 is swung 50 downwardly the projecting portion 37 thereof will be moved upwardly engaging the projection 44 and carrying the link 41 upwardly. As the link 41 moves upwardly, upward pressure will be exerted upon the slide 31 through the compression spring 47, causing the slide 31 to move upwardly to lift the latch releasing trip 6. If the lever 36 is swung upwardly from its neutral position the projection 37 will be moved downwardly 55 against the foot piece 43 of the link 40 moving the link 40 downwardly. The downward movement of the link 40 causes the lever 38 to rock about its pivot 39 and lift the link 41. The upward movement of the link 41 will cause pressure to be exerted on the slide 31 through the compression spring 47 and will thus cause the release of the lock in exactly the same way as upon the downward movement of the lever. When the lever 36 is moved in either direction the two 60 links 40 and 41 are caused to move in downward and upward directions respectively, the same result being obtained by the action of the lever upon the projection 43 as by the action of the lever upon the projection 44. 65 The coil spring 47 is preferably stronger than the return spring 33 of the slide so that in normal operation there will be no yielding between the actuating lever and slide. Whenever excessive pressure is exerted upon 70 the lever due to violent actuation thereof or to the resistance of the movement of the slide the spring 47 will yield and permit relative movement between the lever and slide until the lever has reached its limit of movement and thus protect the door lock mechanism and the lock actuator mechanism against damage which might otherwise be caused by excessive pressures. Means may be provided to prevent the compression 75 spring 47 from reacting on the compression spring 33 which serves to return the slide. To this end slot 46 in the link 41 is so disposed that when the mechanism is in the normal position shown in Figure 8 of the drawing 80 the projections 43 and 44 engage the projection 37 of the lever and the projection 45 of the slide is in engagement with or nearly in engagement with the upper end of the slot 46. This serves to hold the spring 85 47 under a predetermined minimum compression during operation since it prevents the spring from expanding farther than is necessary to bring the projection 45 into engagement with the upper end of the slot 46. 90 The projection 45 being held at all times against the upper end of the slot 46 except when the lever is subjected to excessive pressure, the spring 47 cannot react against the slide 31 to exert a pressure thereon in opposition to the return spring 33 except when 95 more than the normal operating pressure is exerted on the lever 36. 100

The auxiliary counterbalance spring 28 shown in Figs. 5 and 6 may be advantageously employed to counterbalance the weight of the swinging push bar in the double acting mechanism above described, the function of the auxiliary spring in this case being merely to relieve the main actuator 105 110 115 120 125 130

ator mechanism of a portion of the weight of the swinging push bar permitting a lighter return spring to be employed in connection with the actuator slide.

5 Having described my invention, I claim:

1. The combination with a door having a lock casing secured therein, said casing having a lock and a trip member for operating the lock, of an operating device secured to the door beneath the lock casing, said operating device comprising a casing secured to one face of the door, a slide in said casing having a projection adjacent its upper end adapted to engage the trip member of the lock, a spring for moving said slide in one direction and a lever for moving said slide in opposition to the spring.

2. The combination with a door having a lock casing secured therein, said casing having a lock and a trip member for operating the lock, of an operating device for said lock comprising a casing secured to one face of the door below the lock casing, a slide in said casing, a spring acting on said slide, an operating member carried by the casing and movable in two directions, connections between said operating member and slide for actuating said slide in opposition to its spring when said operating member is moved in either direction, and a projection carried by said slide at its upper end and adapted to engage the trip member of the lock.

3. The combination with a door having a lock casing secured therein, said casing having portions extending through opposite faces of the door and having a lock therein provided with a trip member by which it may be operated, of an operating device comprising a casing secured to one face of the door to one side of the projecting portion of the lock casing, a slide carried by the casing, a spring acting in one direction on the slide, a lever adapted to move the slide in opposition to the spring and a lock operating projection on the slide engageable with the trip member of the lock.

4. In a device of the character described, the combination with a door lock having a trip member, of a lock operating device comprising a movable lock operating member having a portion adapted when said member is moved in one direction to engage the trip member of the lock, a spring acting on said operating member, an operating lever, and connections between said lever and operating member acting to shift said operating member in opposition to its spring when the lever is shifted in either direction, said connections including a spring through which the lever acts when moved in either direction.

5. In a device of the character described, the combination with a door having a lock, of a lock actuating mechanism, comprising

a slide operable when shifted in one direction to release the door lock, an actuating lever, and a member having a spring connection with said slide and operable upon movement of said lever in either direction to operate said slide through the spring connection in the direction to release the door lock.

6. In a device of the character described, the combination with a door having a lock, of a lock actuating mechanism comprising a movable lock actuating member, an actuating lever, a second lever pivoted to the casing or a link pivoted to the second lever and having a spring connection with the lock actuating member and means carried by the second lever and link whereby said actuating lever moves said link and slide in a direction to release the lock upon movement of the actuating lever in either direction.

7. A lock operating device comprising a movable lock actuating member, an actuating lever, connections between said lever and an actuating member whereby actuation of the lever in either direction causes the actuating member to move in a direction to release the lock, said connections including a spring acting to cushion the lever when the same is moved in either direction.

8. A lock actuating device comprising a casing, a slide movable in the casing, a centrally pivoted lever extending transversely of the casing, links pivoted to the ends of the lever and extending alongside the slide, one of said links being connected to the slide, transversely extending projections carried by said links, and a movable operating member having a portion extending between said projections and engageable with either.

9. A lock actuating device comprising a casing, a longitudinally movable slide mounted in the casing, a spring interposed between the slide and casing, a transversely extending lever pivoted adjacent its center to the casing, links pivoted to opposite ends of the lever and extending alongside the slide, a spring connecting one of said links to the slide, transversely extending projections carried by the links, and a movable actuating member having a part lying between said projections and engageable with either.

10. A lock actuating device comprising a movable lock operating member, a movable actuating member for shifting the operating member, means for transmitting movement from the actuating member to the operating member, comprising a pair of movable parts engageable with the actuating member on opposite sides thereof, said parts being connected to the slide, and a spring acting upon said parts to normally hold said parts in engagement with the actuating member.

11. A lock actuating device comprising a casing, a longitudinally movable slide mounted in the casing, a spring interposed between the slide and casing, a transversely extending lever pivoted adjacent its center to the casing, depending links pivoted to opposite ends of the lever and extending along opposite sides of the slide, projections extending inwardly from said links, a spring connection between one of the links and the slide, and an actuating lever having a portion lying between the projections of the links. 45
12. A lock actuating device comprising a casing, a longitudinally movable slide mounted in the casing, a spring interposed between the slide and casing, a transversely extending lever pivoted adjacent its center to the casing, depending links pivoted to opposite ends of the lever and extending along opposite sides of the slide, one of said links having an inwardly extending projection adjacent its lower end, the other of said links having a yielding connection adjacent its lower end to the slide and a projection extending inwardly over the projection of the first mentioned link, and an actuating lever having a part extending between said projections. 50
13. A lock actuating device comprising a casing, a longitudinally movable slide in the casing, a spring interposed between the slide and casing, an actuating lever for moving the slide in opposition to the lever and a counterbalance spring for the said lever. 55
14. The combination with a hinged door having a lock, a lock actuator, comprising a casing secured to the door adjacent the lock, a lock actuating slide in the casing, a return spring interposed between the slide and casing, a lever for actuating the slide in opposition to the said spring, a push bar having one end connected to said lever and at its other end to a lever pivoted adjacent the hinge edge of the door, and a counterbalance spring acting on said second mentioned lever. 60
15. A lock actuating device comprising a movable lock actuating member adapted to release the lock upon movement thereof in one direction, an actuating lever, connections between said lever and actuating member whereby actuation of the lever in either direction causes the actuating member to move in a direction to release the lock, said connection including a spring acting to cushion the lever when the same is moved in either direction, and means for retaining said spring at all times under compression. 65
16. A lock operating device comprising a movable lock actuating member adapted when moved in one direction to release the lock, a spring interposed between the actuating member and casing for normally holding the actuating member in inoperative position with respect to the lock, a lever for moving the actuating member in opposition to its spring, and connections between the lever and actuating member through which the actuating member is moved in opposition to its spring upon movement of the lever in either direction, a cushioning spring interposed between the actuating member and said operating connections, and means for preventing said second mentioned spring from reacting upon the actuating member in opposition to said first mentioned spring. 70
- In testimony whereof, I hereunto affix my signature. 75
- WILLIAM B. BOLLES. 80
